UNITED STATES PATENT OFFICE.

CHARLES L. REIZENSTEIN, OF PITTSBURGH, PENNSYLVANIA.

DESIGN FOR A GLASS OR CHINA VESSEL.

54,126.

Specification for Design.

Patented Nov. 4, 1919.

Application filed July 16, 1917. Serial No. 180,943. Term of patent 14 years.

To all whom it may concern:

Be it known that I, CHARLES L. REIZENSTEIN, a citizen of the United States, and residing at 310 South Rebecca St., city of Pittsburgh, county of Allegheny, and State of Pennsylvania, have invented a new, original, and ornamental Design for a Glass or China Vessel, of which the following is a specification, reference being had to the accompanying drawing, forming part thereof.

The figure is a plan view of a glass or china dish showing my new design.

I claim:

The ornamental design for a glass or china vessel, as shown.

CHARLES L. REIZENSTEIN.

Witnesses:

J. R. KELLER,
JOHN F. WILL.
